UNITED STATES PATENT OFFICE.

LEIGHLIN CONROY, OF NEW YORK, N. Y.

BREECH-LOADING GUN.

SPECIFICATION forming part of Letters Patent No. 437,574, dated September 30, 1890.

Application filed December 12, 1889. Serial No. 383,462. (No model.)

To all whom it may concern:

Be it known that I, LEIGHLIN CONROY, a citizen of the United States, residing at New York, in the county and State of New York, have invented new and useful Improvements in Magazine Fire-Arms, of which the following is a specification.

My invention relates to certain new and useful improvements in magazine fire-arms, known as "bolt-guns," or arms wherein a reciprocating breech-block provided with an extractor and firing-pin is used, and I have pointed out said improvements in the following specification and claims and illustrated 15 the same in the accompanying drawings, in which—

Figure 1 represents a longitudinal section, showing the rear portion of the gun with the parts in position after a cartridge has been 20 fired, the empty shell being still in the barrel. Fig. 2 is an addition to Fig. 1, showing the front end of the gun when the feed-slide is in the forward position. Fig. 3 is a transverse section in the plane $x\ x$, Fig. 1. Fig. 4 is a 25 longitudinal section showing the bolt partially drawn back. Fig. 5 is a transverse section in the plane $x'\ x'$, Fig. 4. Fig. 6 is a plan or top view of the feed-slide and follower detached. Fig. 7 is a similar view to Fig. 4 when the 30 bolt has been drawn back completely, on a larger scale than the previous figures. Fig. 8 is a similar view to Fig. 2 when the feed-slide is drawn back. Fig. 9 is a transverse section in the plane $y\ y$, Fig. 8. Fig. 10 is a 35 horizontal section in the plane $z\ z$, Fig. 7. Fig. 11 is a vertical section in the plane $z'\ z'$, Fig. 10, the bolt having been removed to expose the parts below. Fig. 12 is a transverse section in the plane $z^2\ z^2$, Fig. 10. Fig. 13 is a 40 longitudinal central section of the rear portion of the gun when the same is adjusted for a single-loader. Fig. 14 is a transverse section in the plane $x^2\ x^2$, Fig. 13. Fig. 15 is a plan or top view of the carrier detached. Fig. 16 is a transverse section in the plane $x^3\ x^3$, Fig. 15. Fig. 17 is a plan view of the 45 locking-sleeve carried by the bolt. Fig. 18 is a detached elevation of the feed-pawl and the stop-pawl.

In the drawings, the letter A designates the barrel, which is secured in the receiver A'. B is the bolt, and C is the magazine, which

is situated beneath the barrel, and into which fresh cartridges may be introduced through the breech of the gun when the bolt is drawn 55 back.

The cartridges are fed toward the breech by means of a follower D, which is actuated by the feed-slide E, as will be presently explained. The follower is composed of two 60 heads $a\ a$, which are connected by two plates $b\ b$. (See Figs. 6 and 9.) Between these plates are situated two pawls $c\ d$, which swing on a common pivot c^0 , the pawl c being the feed-pawl and the pawl d the stop-pawl. From 65 the hub of the feed-pawl c extends a tail c' into a groove c^2 in the bore C', to which the magazine C is secured.

In the bottom part of the magazine is firmly secured a rack-bar d' , which is provided with 70 ratchet-teeth d^2 , Fig. 6, the distance between which is equal to the length of the cartridges, and which are in position for engagement with the stop-pawl d .

The feed-slide E extends on the side of the 75 fixed rack-bar d and is provided with ratchet-teeth c^3 , the distance between which is equal to that between the teeth d^2 of the rack-bar d' , and which are in position for engagement with the feed-pawl c .

The stop-pawl d is provided with a slot d^3 , Figs. 8 and 18, and the feed-pawl c is provided with a pin d^4 , which engages the slot d^3 , so that when this feed-pawl is raised a sufficient distance the stop-pawl is thrown out of engagement with the rack-bar d' , and when the feed-pawl is depressed it carries the stop-pawl along. The pin d^4 , however, has sufficient play in the slot d^3 , so that when the feed-bar E is moved forward and the feed-pawl is raised 90 thereby the stop-pawl is not thrown out of engagement with the stationary rack-bar d' , and the stop-pawl will only be thrown out of engagement with the stationary rack-bar when the magazine has been exhausted, as 95 will be presently explained. Both pawls are exposed to the action of spring-actuated stops $d^5\ d^6$, respectively, which extend into notches in the hubs of the pawls and serve to retain said pawls with a force commensurate to their 100 springs when the pawls are down and when they are up.

The feed-slide E receives a reciprocating motion by means of a dog F, pivoted to the

bolt B. When the bolt is in its forward position, Fig. 1, the dog F engages a recess e^0 in the rear portion of the feed-slide, Figs. 1 and 6, being depressed by the action of a spring 5 e' . At the same time the feed-dog c of the follower D is in engagement with the feed-slide, Fig. 2. When the bolt B is drawn back to the position shown in Fig. 4, the follower D is drawn inward by the feed-slide, and a 10 cartridge is pushed inward so that it rests upon the carrier L, while the projection f^0 of the dog F strikes the ridge G, so that the said dog is thrown out of gear with the feed-slide E, Figs. 4 and 7. The carrier L is trough-shaped, 15 Figs. 15 and 16, and it swings on pivots l. When the bolt B is moved from the position shown in Fig. 4 to that shown in Fig. 7, the projection H strikes the tail of the carrier, and the front portion of said carrier, which carries 20 a cartridge, is raised to the position shown in Fig. 7, and the cartridge is ready to be pushed into the barrel by the subsequent forward movement of the bolt.

The carrier L is locked in its raised position 25 by a spring-catch I, Fig. 7, which is situated beneath the barrel, and when the bolt is moved forward, so as to close the breech, this spring-catch is pushed back to the position shown in Fig. 1, and the carrier L being released 30 returns to its original position, while the follower D remains stationary, being held in position by the stop-pawl d. As the bolt is moved forward, the feed-slide is pushed forward in the magazine, and when the bolt 35 is again drawn back the next cartridge is pushed upon the carrier. When the magazine has been exhausted, the tail c' of the feed-pawl strikes the shoulder c' at the inner end of the groove c², and both pawls c d are raised 40 and retained in this position by the spring-stops d⁵ d⁶, Fig. 4, so that by bringing the gun in an inclined position the follower D can be made to slide to the forward end of the magazine and fresh cartridges can be introduced. 45 When the follower reaches the forward end of the magazine, the tail c' strikes the shoulder c⁸, Fig. 2, and both pawls are returned to their working positions. A stop c⁹ limits the backward movement of the tail c'.

50 When the feed-slide E is in its forward position, Fig. 1, the dog F, which engages the recess e^0 in the rear portion of the feed-slide, is in position to be thrown out of engagement with the feed-slide by the action of a lever J, 55 which has its fulcrum on a pivot j, and the tail end of which engages a recess j⁰ in the hub of a finger-lever K, which has its fulcrum on a pivot k. If the finger-lever is moved in the reverse direction indicated by the arrow 60 shown near it in Fig. 1, the lever J throws the dog F out of engagement with the feed-slide, and the tail end of the lever K acts upon the carrier L and moves the same up into the breech and retains it in the position which 65 said carrier occupies in Fig. 13. The bolt B can now be moved backward and forward

without actuating the feed-slide, and the gun can be used as a single-loader.

On the rear end of the bolt B is fitted a sleeve M, from which extends a handle N, and which is retained in position by a screw-cap O. (See Figs. 1 and 4.) On the body of the sleeve M is cut a screw-thread, portions of which are cut away, so as to form a series of threaded segments $m m^2 m^4$, which alternate with the plain segments $m' m^3 m^5$, Figs. 3, 5, and 17. On the rear end of the receiver A' is cut a screw-thread to engage the screw-thread on the sleeve M, and this screw-thread in the receiver is formed into plain segments and threaded segments corresponding to the segments $m m' m^2 m^3 m^4 m^5$ on the sleeve, but disposed in such a manner that when the handle N of the sleeve occupies a vertical position the threaded segments $m m^3 m^4$ stand opposite the plain segments in the receiver, and if the bolt B is pushed forward to the position shown in Fig. 1 the threaded segments $m m^2 m^4$ of the sleeve enter the corresponding plain segments in the receiver. When the handle 90 N is then turned to the position shown in Fig. 1, the threaded segments $m m^3 m^4$ of the sleeve engage the adjoining threaded segments in the receiver, and the front end of the bolt is firmly pressed up against the rear end of the barrel and held there while the gun is fired. By these means the bolt can be firmly locked without turning the same, and when the bolt is locked the handle N does not obstruct the 95 sight.

On the bolt are secured the extractors P. (See Figs. 7, 10, 11, and 12.) They are fitted into recesses p in the body of the bolt and held in position by screws p', which extend through slots p² in the shanks of the extractors, so 105 that said extractors can slide a short distance in the direction of their length. When the carrier L, together with the cartridge, is raised to the position shown in Fig. 7, the rim of the cartridge is forced between the extractor, (see 110 Fig. 10,) so that the hooks p³ of said cartridges are in front of the rim of the cartridge. If the bolt is now pushed forward so as to close the breech, the hooks p³ of the extractors enter the recesses p⁴ in the rear end of the barrel, 115 Fig. 7, and when the gun has been fired and the bolt is moved back the hooks p³ carry the empty shell of the cartridge back into the breech, whence it can be readily removed.

From this description it will be seen that 120 the rims of the cartridges are thrown in engagement with the extractors by the action of the carrier, and it is only necessary to move the extractors far enough out beyond the end of the bolt, Figs. 7 and 10, so that if a cartridge is raised up by the carrier the rim of said cartridge will occupy a position behind the noses of the extractors. When the bolt is pushed forward, the cartridge is driven into the rear end of the barrel and the extractors 125 enter the recesses p⁴, and as their front ends strike the ends of these recesses they (the ex-

tractors) slide back, and the cartridge is retained in close contact with the front of the bolt, Fig. 1. The extractors do not spring over the rims of the cartridges, and the recesses p^4 are made just deep enough to be filled up completely by the front ends of the extractors, leaving no vantage when the cartridge is fired. If the bolt is moved back the extractors remain stationary for a short time, and by the time the screws p' strike the rear ends of the slots p^2 , Fig. 10, the bolt has acquired sufficient momentum to cause the extractors to throw the cartridge out with the required velocity.

15 What I claim as new, and desire to secure by Letters Patent, is—

1. In a magazine fire-arm, the combination, with the barrel A, the receiver A', and the bolt B, of the magazine C beneath the barrel, 20 the feed-slide E, provided with ratchet-teeth, the rack-bar d', fixed in the magazine, the follower D, the pawls c d, mounted in the follower, and the dog F, carried by the bolt and constructed to engage the feed-slide, substantially as described.

25 2. The combination, with the barrel A, the

receiver A', the bolt B, and the magazine C, of the feed-slide E, the dog F, carried by the bolt and constructed to engage the feed-slide, the projection G to throw the dog F out of gear with the feed-slide, the carrier L, and the projection H on the bolt for actuating the carrier, substantially as described.

3. The combination, with the barrel A, the receiver A', the bolt B, and the magazine C, 35 of the carrier L, the projection H on the bolt, and the latch I in the front part of the receiver, substantially as described.

4. The combination, with the barrel A, the receiver A', the bolt B, and the magazine C, 40 of the feed-slide E, the dog F, carried by the bolt and constructed to engage the feed-slide, the lever J, for throwing the dog F out of gear with the feed-slide, the finger-lever K, and the carrier L, substantially as described. 45

In testimony whereof I have hereunto set my hand in the presence of two subscribing witnesses.

LEIGHLIN CONROY.
